UNITED STATES PATENT OFFICE.

AUGUSTUS A. GREENE, OF PAWTUCKET, RHODE ISLAND.

DESIGN FOR AN ORNAMENTAL VEST-CHAIN.

SPECIFICATION forming part of Design No. 32,807, dated June 12, 1900.

Application filed May 10, 1900. Serial No. 16,233. Term of patent 7 years.

To all whom it may concern:

Be it known that I, AUGUSTUS A. GREENE, a citizen of the United States, residing at Pawtucket, in the county of Providence and State of Rhode Island, have invented a certain new and original Design for Ornamental Vest-Chains, of which the following is a specification, reference being had therein to the accompanying drawing, forming a part thereof.

10 As shown in the drawing, the material features of my design are a short guard-chain and bar, pendent from which is a fob ornament in conjunction with vest-chains extending from either side of the fob ornament.

15 In detail my new chain may be described as follows: Pendent to a bar is a fob orna-

ment consisting of a series of vertical chains joined at their extremities by bars and pendent therefrom a charm. To the upper bar at either extremity are attached vest-chains, 20 extending at an angle from the fob-chain.

Having thus described my invention, what I claim as new, and desire to secure by Letters Patent, is—

The design for an ornamental vest-chain, 25 as herein shown and described.

In testimony whereof I have affixed my signature in presence of two witnesses.

AUGUSTUS A. GREENE.
